UNITED STATES PATENT OFFICE.

ROBERT OCHSNER, OF NEW HAVEN, CONNECTICUT

LATCH FOR AUTOMOBILE-DOORS

1,085,471.

Specification of Letters Patent

Patented Jan. 27, 1914.

Application filed May 22, 1913. Serial No. 769,164

To all whom it may concern:

Be it known that I, ROBERT OCHSNER, a citizen of the United States, residing at New Haven, in the county of New Haven and State of Connecticut, have invented a new and useful Improvement in Latches for Automobile-Doors; and I do hereby declare the following, when taken in connection with the accompanying drawings and the characters of reference marked thereon, to be a full, clear, and exact description of the same, and which said drawings constitute part of this application, and represent, in—

15 Figure 1 a view in inside elevation of an automobile door-lock constructed in accordance with my invention, shown as applied to an automobile door the main body of which is broken away. Fig. 2 a corresponding view showing the handle turned downward for the retraction of the latch bolt. Fig. 3 a detached plan view of the vertically adjustable handle-case with the handle mounted therein. Fig. 4 a detached reverse view of the adjustable handle-case with its inner plate removed. Fig. 5 a broken view in vertical section on the line $a-b$ of Fig. 1 on an enlarged scale. Fig. 6 a detached reverse view of the latch-bolt lock proper.

My invention relates to an improvement in that class of locks designed especially for use on the doors of automobiles, the object being to produce an extremely simple, durable and reliable lock easy to apply, presenting a good appearance and constructed with particular reference to being readily adjustable to fit automobile doors varying widely as to the position of the lock and the handle.

With these ends in view my invention consists in an automobile door-lock having certain details of construction and combinations of parts as will be hereinafter described and pointed out in the claims.

The lock proper or the latch-bolt locks, as it may be called, may be of any approved design and construction as long as it is of the type in which the latch-bolt 2 is operated by an upwardly extending lever 3. As shown the latch-bolt 2 is formed with a long shank 4 formed about midway of its length with an offset 5 for the reception of the lever 3 and to form a bearing 6 therefor. The lever is pivotally hung, upon a screw-stud 7 passing through its extreme lower

end and mounted in the lock-case 8 and its plate 9. A helical spring 10 engaging with the shank 5 of the bolt is provided for normally maintaining the same in its projected or shot position; while a helical spring 11 engaging with the lever is provided for normally holding the same in its closed position and against the stop 12, whereby the lever is prevented from rattling during the motion of the car. When the lever 3 is retracted against the tension of the spring 11, its outer edge engages with the bearing 6 produced by the formation of the offset 5. As shown, the lock is provided with a roll-back 18 engaging with a lug 14 depending from the bolt 4, this roll-back being formed with a square opening 15 for the reception of the square shank of the handle.

I would have it distinctly understood, however, that I do not limit myself to the particular latch-bolt mechanism described, since any self-contained latch bolt mechanism operated by an upwardly extending lever will answer the purpose of my invention. 80

As my improved lock is made and supplied to the trade, the lever 3 is made long enough to adapt the lock to be used in doors of the greatest height, the idea being that 85 after the lock reaches the hands of the consumer the lever will be cut off according to the distance between the position of the lock on the door and the desired position of the operating handle thereon.

In order to adapt my improved lock to be used with doors in which the separation of the handle and lock varies, I employ a self-contained vertically adjustable roll-back case consisting of an outer plate 16 formed near its ends with vertical transversely arranged ribs 17 forming bearings for the inner plate 18 which is secured to the outer plate by screws 19 entering the threaded central portions of the said ribs. Those portions of the plate 16 lying outside of the bearing-ribs 17, form fastening flanges 20 having screw-holes 21 and provided for fastening the roll-back case in right position to the inner face of an automobile door 22, it being understood that the inner face of the door is formed with a recess 23 narrower than the full length of the plate 16 the flanges 20 of which extend beyond the side walls of the recess and bear upon the flush portions of the door. Between the plates 16 and 18, I mount a roll-back consisting of a hub

24 and a cam-like operating arm 25 which engages directly with the outer edge of the lever 3 at one point or another thereupon, according to the relative position of the 5 roll-back case with respect to the lock proper which is located in the lower portion of the recess 23 in the door 22 and secured in place, as shown, by screws 26. The hub 24 of the roll-back is formed with an outwardly 10 extending square shank 27 for the reception of the hub 28 of the curved door handle 29 which is secured in place by means of a screw 30 entering the threaded outer end of the shank 27.

15 In order that the inside of the door 22 may be neatly covered with upholstery so as to entirely conceal the roll-back case and lock, I employ a spacing ring 31 which is fitted over an annular shoulder 32 at the 20 base of the shank 27. Upon the ring 31 I place a finishing washer 35 which, by preference, will be finished to match other trimmings of the car. I thus secure a space 33 between the plate 16 and the washer 35 for 25 the reception of the upholstery 34 where it is perforated for the projection through it of the shank 27 of the roll-back 24.

The lever 3 extends directly upward between the plates 16 and 18 of the roll-back 30 case which may be raised or lowered with respect to the lever until the handle has been positioned properly with relation to the lock. Any excess length of lever then projecting above the roll-back case is cut off.

35 It will be seen that as there is no direct connection between the plates 16 and 18 and the lever 3, the roll-back case may be raised and lowered with respect to the lever as desired, the only requirement being that in 40 the finished position of the roll-back case the arm 25 of the roll-back shall engage with the lever.

In using the lock, the depression of the handle 29 will effect the retraction of the 45 latch-bolt 2 through the medium of the lever 3 and against the combined tension of the springs 10 and 11.

I claim:

1. In an adjustable lock for automobile

doors, the combination with a self-contained 50 latch-bolt lock provided with a latch-bolt and an upwardly extending swinging lever for the operation thereof, of a self-contained vertically movable roll-back case made independent of the said latch-bolt 55 lock for attachment to an automobile door at any desired height above the said latch-bolt, and adapted to have the said lever thereof pass upward through it and provided with a roll-back for co-action with 60 the said lever and with a handle for turning the roll-back.

2. In an adjustable lock for automobile doors, the combination with a latch-bolt lock provided with a latch-bolt and an upwardly extending swinging lever for the operation thereof, of a roll-back case made independent of the said latch-bolt lock, vertically adjustable with respect thereto and comprising inner and outer plates secured together, 70 one of the plates being provided at its ends with fastening flanges and the two plates being separated from each other to permit the lever to extend upward between them, and a roll-back mounted in the said plates 75 of the said independent vertically movable roll-back case and co-acting with the said lever.

3. In an adjustable lock for automobile doors, the combination with a latch-bolt 80 lock provided with a latch-bolt and an upwardly extending lever for the operation thereof, of a roll-back case adapted to have the lever pass upward through it so as to permit the case to be vertically adjustable 85 with respect to the lever, a roll-back mounted in the said case and provided with an outwardly projecting stem, a handle for application to the said stem, and a spacing-ring and finishing-washer interposed between the roll-back case and the handle.

In testimony whereof, I have signed this specification in the presence of two subscribing witnesses.

ROBERT OCHSNER.
